(57) **CLAIM**

The ornamental design for a universal projector mount, as shown and described.

DESCRIPTION

FIG. 1 is a front perspective view of a universal projector mount according to the invention;

FIG. 2 is a top plan view of the universal projector mount depicted in FIG. 1;

FIG. 3 is a bottom plan view of the universal projector mount depicted in FIG. 1;

FIG. 4 is a front elevation view of the universal projector mount depicted in FIG. 1;

FIG. 5 is a side elevation view of the universal projector mount depicted in FIG. 1;

FIG. 6 is a rear elevation view of the universal projector mount depicted in FIG. 1; and,

FIG. 7 is an opposing side elevation view of the universal projector mount depicted in FIG. 1.

The broken line depiction of structure is included for the purpose of illustrating environment and forms no part of the claimed design.
